UNITED STATES PATENT OFFICE.

ANDREW B. HERD, OF PHILIPSBURG, PENNSYLVANIA.

JACK-O'-LANTERN.

SPECIFICATION forming part of Letters Patent No. 715,379, dated December 9, 1902.

Application filed January 31, 1902. Serial No. 92,054. (No model.)

To all whom it may concern:

Be it known that I, ANDREW B. HERD, a citizen of the United States, residing at Philipsburg, in the county of Center and State of Pennsylvania, have invented a new and useful Jack-o'-Lantern, of which the following is a specification.

The invention relates to the general class of transparencies, and particularly to decorative and grotesque illuminating devices or lanterns commonly called "jack-o'-lanterns;" and the object in view is to provide a simple and inexpensive device of this class which may be constructed of sheet material, such as cardboard or its equivalent, the same having means for giving access to the contained illuminating device and with means for protecting the light from drafts of air when the lantern is in motion, as in torch-light processions and the like.

Further objects and advantages of the invention will appear in the following description, and the novel features thereof will be particularly pointed out in the appended claims, it being understood that various changes in the form, proportion, and the minor details of construction may be resorted to without departing from the spirit or sacrificing any of the advantages of this invention.

In the drawings, Figure 1 is a front view of a lantern constructed in accordance with the invention. Fig. 2 is a rear perspective view of the same. Fig. 3 is a vertical central sec-

35 tional view.

Similar reference characters indicate corresponding parts in all the figures of the drawings.

The front wall or face 10 of the lantern is 40 preferably circular and is superficially ornamented to represent a pumpkin and is provided with light-exit openings—such as those shown at 11, 12, 13, and 14—arranged and having configurations representing the features 45 of a face. For the protection of the illuminating device these openings are covered by semitransparent or translucent shields 15, which may be of colored paper or glass or the equivalent thereof. Secured to the rear side 50 of this front or face and combining therewith to form the light receptacle or cage is a box 20, formed of sheet material, and preferably

of cardboard or its equivalent, the same having a bottom wall 22, provided with air-inlet openings 24, a top wall 25, having a vent 26, 55 a rear wall 27, preferably integral with the top and bottom walls, and side walls also preferably integral with the rear wall. One of these side walls, which is connected at the fold-line 29 with the rear wall, forms a door 60 30, said fold-line constituting a hinge to permit the opening of the door to give access to the interior of the box and facilitate arranging a light-giving or illuminating device, such as a candle 40, in a rest or holder 23, which 65 is secured to the bottom wall. The preferred means of attaching the top, bottom, and fixed side wall of the box to the front wall or face consist of integral flaps or flanges 21, which may be pasted or otherwise attached to the 70 rear surface of said front wall, and the door 30 is preferably provided at its free front edge with a flap 33, adapted to bear frictionally against the rear surface of the front wall, and thus hold the door in its closed position. A 75 strip or grip 34 is also provided to facilitate opening the door. To prevent the ingress of air through the intervals between the upper and lower edges of the door and the adjacent walls of the box, guard-flanges 31 and 32 are 80 provided on said edges of the door to close into the box and lie in contact with said top and bottom walls thereof, as shown clearly in Fig. 3.

The box forming the receptacle for the illuminating device is preferably rectangular in contour and is of such dimensions as to lie wholly within (and preferably considerably within) the contour of the face or front wall, as shown clearly in Fig. 2, whereby the portion of the face or front wall which projects above the top wall of the box forms a wind-guard for protecting the opening or vent 26, and the portion of said face or front wall which projects below the bottom wall 22 constitutes 95 a front inner guard to protect the inlet-openings 24 during the forward movement of the device. Depending from the box near its rear wall and preferably secured to said rear wall is a member 28, constituting a rear wind-guard for the openings 24, and also a rest, of which the lower edge is straight and is in the same horizontal plane, so as to combine with said lowermost point of the face or front wall 100

to constitute a base upon which the lantern may stand in an upright position.

While in the construction illustrated the box is formed of two sections—namely, an upper section and a lower section—of which the adjacent edges are overlapped, as shown at 50, it will be understood that the entire box may be struck from a single blank of sheet material. The advantage in constructing the 10 same of two sections secured together at the overlap by paste or other means is that transverse rigidity is afforded to prevent collapsing or destructive bending or indentation of the receptacle for the illuminating device.

15 When the lantern as above described is constructed of cardboard or its equivalent, it is obvious that it may be manufactured at a small cost, and yet the parts thereof are so related as to perform their functions efficiently, and the liability of the ignition of the receptacle from the flame of the illuminating device is reduced to the minimum by reason of the wind-guards provided to protect the air-inlet and ventilating openings.

20 25 In carrying the lantern in a torch-light procession, such as campaign-parades, &c., the face, consisting of the disk or plate, should be held in advance, or facing in the direction of movement or facing in the direction from which the wind is moving, so that the projecting periphery of the disk will deflect the wind and prevent it from passing through the inlet and vent openings in the bottom and top walls of the lantern-box. In this way the article, though made of combustible material, is 30 35 preserved, the flickering or blowing of the flame, which would cause it to ignite the walls, being avoided.

Having described the invention, what is 40 claimed is—

1. A lantern having a receptacle for an illuminating device, provided in its walls with air-inlet and ventilating openings and having a front plate peripherally extended 45 beyond the walls of the receptacle to form front wind-guards in advance of said inlet and ventilating openings, and a rear wind-guard depending from the bottom wall of the receptacle in rear of said openings and having its lower edge arranged in a common horizontal plane with the lowermost portion of the edge of said front plate to form a rest or base.
2. A lantern having a front plate, and a box

secured to the rear surface of said front plate, 55 said box consisting of a folded blank of sheet material having its front edges attached to the surface of the front plate and provided with a side door hinged at its rear edge, and in frictional contact at its front edge with the 60 rear surface of the front plate to movably hold it in its closed position.

3. A lantern having a front plate and a box secured to the rear surface of the front plate and consisting of a rear wall, and top, bottom and side walls connected respectively with the edges of the rear wall, and one of said side walls having a flanged front edge for frictional contact with the rear surface of the front plate to maintain it in its closed 70 position, and the remaining top, bottom and side walls being secured at their front edges to the rear surface of the front plate.

4. A lantern having a front plate, and a box secured to the rear surface of the front plate, 75 said box being constructed of yielding sheet material and having a side wall hinged at its rear edge to the body portion of the box and provided with a flanged front edge for frictional contact with the rear surface of the 80 front wall, and flanged inturned upper and lower edges to engage the top and bottom walls of the box.

5. As a new article of manufacture, a jack-o'-lantern having a front plate and a box secured to the rear surface of the front plate and consisting of a rear wall, top and bottom walls respectively provided with ventilating and air-inlet openings, and fixed and movable side walls, the top and bottom walls and 90 the fixed side wall being secured at their front edges to the rear surface of the front plate, and the movable wall being hinged at its rear edge to the rear wall and provided with front, top and bottom flanges for engagement respectively with the rear surface of the front wall and the top and bottom walls, and a rear wind-guard depending from the rear wall and terminating in the horizontal plane of the lowermost point of the front 100 plate.

In testimony that I claim the foregoing as my own I have hereto affixed my signature in the presence of two witnesses.

ANDREW B. HERD.
